UNITED STATES PATENT OFFICE.

JOSEPH A. WARD, OF CROWELL, TEXAS.

THROTTLE-CONTROL MECHANISM.

Application filed June 24, 1922. Serial No. 570,626.

To all whom it may concern:

Be it known that I, JOSEPH A. WARD, a citizen of the United States, residing at Crowell, in the county of Foard and State of Texas, have invented new and useful Improvements in Throttle-Control Mechanism, of which the following is a specification.

This invention relates to governors, and contemplates the provision of a governor mechanism primarily designed for use in conjunction with tractors, whereby the throttle is automatically controlled to prevent the motor from operating beyond a predetermined speed, the mechanism being susceptible of adjustment to vary the speed at which the motor may operate without being effected incident to the operation of the governor mechanism.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

Figure 1 is a side elevation of my invention, part being shown in section; Figure 2 is an enlarged longitudinal sectional view of the same; Figure 3 is a transverse sectional view taken on line 3—3 of Figure 2; Figure 4 is a rear end elevation of the device; Figure 5 is a transverse sectional view taken on line 5—5 of Figure 2, and Figure 6 is an end elevation reverse to Figure 4.

The mechanism forming the subject matter of the present invention includes a shaft 10 which is provided with a longitudinal bore 11 to receive a rod 12, this rod projecting beyond both ends of the shaft 10 and provided at one end with a head or enlargement 13. The purpose of this rod 12 will be hereinafter described. One end of the shaft is threaded to accommodate a nut 14, and this end of the shaft is reduced to provide a shoulder 15. Surrounding the shaft and interposed between the nut 14 and shoulder 15, is a collar or support 16, which is formed with an extension 17, on which is fulcrumed as at 18 a bell crank lever as shown. One branch 19 of this bell crank lever extends across the adjacent end of the shaft 10, while the other branch 20 is connected to a shaft 21 through the instrumentality of a connect-

ing rod 22. The shaft 21 is journaled in suitable bearings 23, and one end of the shaft 21 is offset as at 24, this offset portion being connected with the rod 22.

The other end of the shaft 21, is also offset as at 25, and leading from this offset extremity is a link 26 which is connected with the throttle valve indicated generally at 28. A coiled spring 29 is connected to one end of a bolt 30 which is passed through a portion of the offset extremity 24 of the shaft 21, and has associated therewith a nut 32 to vary the tension of the spring, the latter being connected to a fixed point as at 33. The rotation of the shaft 21 is automatically controlled incident to the movement of the rod 12 longitudinally of the shaft 10, and this rod 13 is only actuated when the motor of the tractor (not shown) operates at a predetermined speed. When the rod 12 is moved in one direction to the shaft 10, it operates the bell crank lever, and turns the shaft 21 against the tension of the spring above described, thereby partly closing the throttle valve. When the speed of the motor is reduced, the spring functions to reverse the movement of the shaft 21, returning the pin 12 to its normal position.

The shaft 10 supports a block or casting 35 which is recessed as at 36 to accommodate the ball bearing 37 on one end of the shaft 10 as illustrated. This block or casting 35 has also pivoted thereon, a plurality of arms 38 which operate in grooves 39, and each arm supports a weight 40. These weights are arranged adjacent the shaft 10, wholly beyond one end of the block or casting 35. Each arm includes an offset end portion 41, and these portions 41 terminate directly behind the head or enlargement 13 of the rod 12.

The block or casting 35 is adapted to be arranged within the belt pulley 42 of the tractor, and bolted or otherwise secured thereto by fastening elements which are adapted to be passed through openings 44 provided in the attaching flange 45, so that the block 35 rotates in unison with the belt pulley. Manifestly, when the motor operates beyond a predetermined speed, the weights 40 are moved outwardly moving their supporting arms on their pivots, and causing the offset extremities 41 to shift the rod 12 longitudinally of the shaft 10, and thus impart movement to the shaft 21 to partially close the throttle valve as above de-

scribed. It will be noted, that by adjusting the nut to vary the tension of the spring 29, that the mechanism can be regulated so as to allow the motor to operate at any desired speed, before the governor mechanism is brought into use. A spring 47 provides a connection between the hand lever 48, and the adjacent offset extremity 25 of the shaft 21, so that the latter can be operated by means of the said hand lever.

While it is believed that from the foregoing description, the nature and advantages of the invention will be readily apparent, I desire to have it understood that I do not limit myself to what is herein shown and described, and that such changes may be resorted to which desired as fall within the scope of what is claimed.

What I claim is:—

20 A device of the character described comprising a hollow pulley, a tubular shaft passing through the hollow pulley, a cap closing

one face of the hollow pulley and provided with a recess and further provided with a plurality of longitudinal grooves, a plurality of bell crank levers pivoted to the cap and each having one leg normally disposed within one of the grooves and its other leg projecting into the recess, weight elements carried by the inner ends of the bell crank levers and disposed in the hollow pulley, a longitudinally movable rod passing through the tubular shaft and having one end disposed in the recess and adapted to be engaged by the last mentioned legs of the bell crank levers upon movement of the same in one direction, and a mechanism actuated by the opposite end of the longitudinally movable rod upon actuation of the same by the bell crank levers, the latter being actuated by the weight elements upon over speeding of the hollow pulley.

In testimony whereof I affix my signature.

JOSEPH A. WARD.
